UNITED STATES PATENT OFFICE.

CLARENCE B. CUMMONS, OF CHARLESTON, MISSOURI.

SCAFFOLD.

SPECIFICATION forming part of Letters Patent No. 745,094, dated November 24, 1903.

Application filed June 24, 1903. Serial No. 162,914. (No model.)

To all whom it may concern:

Be it known that I, CLARENCE B. CUMMONS, a citizen of the United States, residing at Charleston, in the county of Mississippi, State 5 of Missouri, have invented certain new and useful Improvements in Scaffolds; and I do hereby declare the following to be a full, clear, and exact description of the invention, such as will enable others skilled in the art to which 10 it appertains to make and use the same.

This invention relates to scaffolds; and it has for its object to provide a scaffold which may be used in connection with telegraph-poles, trees, or the corners of houses where 15 the construction of the house will permit.

A further object of the invention is to provide a scaffold that may be readily applied and removed, which may be easily adjusted, which will be simple and cheap.

20 In the drawings forming a portion of this specification, and in which like numerals of reference indicate similar parts in the several views, Figure 1 is a top plan view of the scaffold, showing it in position upon a tree, the 25 latter being illustrated in transverse section. Fig. 2 is a side elevation. Fig. 3 is a front elevation.

Referring now to the drawings, the present scaffold comprises a bracket including an 30 angular member consisting of the upright 5, from the upper end of which extends horizontally the arm 6, having its free end curved slightly upwardly, as shown at 7. A brace 8 connects the lower end of the upright 5 with 35 the free end portion of the arm 6, the rivet or bolt 8', which connects the brace with the upright, serving to connect to the lower end of the upright the arc-shaped rest-plate 9, which is disposed transversely of the upright.

40 The rivet or bolt that connects the brace with the arm 6 serves also to connect the transverse bar 10 upon the upper face of the arm, the ends of this transverse bar being curved slightly upwardly, as shown at 11 and 12. 45 The outer end portion of the arm 6, together with the transverse bar, forms a support for a seat 13.

Disposed transversely of the inner end portion of the arm 6 is a yoke-plate 15, the ends 50 of which extend upwardly and have pulley-wheels 16 attached to their extremities, the casings of these pulley-wheels being held rig-

idly. To hold the yoke-plate to the arm 6, a clamping-plate 18 is bolted to the under side thereof and passes under the arm, the bolts 18' 55 for this clamping-plate passing also through a second plate 19, which is disposed above the yoke-plate and between which and the yoke-plate are disposed the stems of hooks 19' and 20, which are pivoted upon the outermost 60 clamping-bolts. The bills of the hooks lie beyond the arc-shaped rest-plate, and their extremities project normally forwardly, so that the hooks may be separated and engaged part way around a tree or pole to which the scaffold 65 is to be attached, the rest-plate at such time lying against the tree or pole below the hooks. Owing to the shape of the hooks, the strain to which they are subjected when a load is placed upon the seat serves to sink the hooks into the 70 tree or pole, so that they are held more firmly.

The hooks are held normally and yieldably in close relation by means of a helical spring 21, which is connected to the hooks at points between their bills and their pivots. The 75 stems of the hooks are continued beyond their pivots in the form of finger-pieces or handles 22. These finger-pieces or handles may be grasped and pressed toward each other, which movement serves to separate the hooks, so 80 that the scaffold may be withdrawn from the tree or pole with which it may be engaged. The manner of attaching and detaching the scaffold will be readily understood and its 85 utility will be appreciated. Through the pulleys at the end of the yoke-plate are passed cords 23, which hang down from the scaffold. These cords are used in hoisting any article or material that may be needed by the person 90 at work upon the scaffold.

It will be noted that the present scaffold may be attached at various heights with ease and may be as readily detached, it being understood that in practice modifications of the specific construction shown may be made and that any suitable materials and proportions 95 may be used for the various parts without departing from the spirit of the invention.

What is claimed is—

1. A scaffold comprising a bracket consisting of an upright, an arm extending longitudinally therefrom and a brace connecting the lower end of the upright to the free end portion of the arm, an arc-shaped rest-plate 100

- connected to the lower end of the upright and disposed transversely thereto, a bar connected to the outer end portion of the said arm and disposed transversely thereto, said bar having its ends curved slightly upward, a yoke-plate disposed transversely of the inner end portion of the said arm, the ends of said yoke-plate being bent upward, pulley-wheels attached to ends of the said yoke-plate, cords passing around the pulley-wheels, said cords being adapted for hoisting, a clamping-plate bolted to the under side of the yoke-plate and adapted to pass under the arm, a second plate disposed above the yoke-plate, and hooks having stems pivoted between the last-named plate and the yoke-plate, the said hooks being extended beyond their pivots in the form of handles.
- 15 2. A scaffold comprising a bracket consisting of an upright, an arm extending horizontally therefrom, and a brace connecting the lower end of the upright to the free end portion of the arm, an arc-shaped rest-plate connected to the lower end of the upright and disposed transversely thereto, a bar connected to the outer end portion of the said arm, and

disposed transversely thereto, said bar having its ends curved slightly upward, a yoke-plate disposed transversely of the inner end portion of the said arm, the ends of said yoke-plate being bent upward, pulley-wheels attached to ends of the said yoke-plate, cords passing around the pulley-wheels, said cords being adapted for hoisting, a clamping-plate bolted to the under side of the yoke-plate and adapted to pass under the arm, a second plate disposed above the yoke-plate, hooks having stems pivoted between the last-named plate and the yoke-plate, and a spring connected to the hooks for the purpose of holding the said hooks yieldably in closed relation.

In testimony whereof I affix my signature in presence of two witnesses.

CLARENCE B. CUMMONS.
